UNITED STATES PATENT OFFICE.

ALVAH C. ROEBUCK, OF WOODSTOCK, ILLINOIS.

TYPE-WRITER.

1,149,293.

Specification of Letters Patent. Patented Aug. 10, 1915.

Application filed January 17, 1914. Serial No. 812,618.

To all whom it may concern:

Be it known that I, ALVAH C. ROEBUCK, a citizen of the United States, residing at Woodstock, in the county of McHenry and State of Illinois, have invented certain new and useful Improvements in Type-Writers, of which the following is a specification.

This invention relates to typewriters and more particularly to type bar pivots. The principal object of the invention is to provide new and improved means for pivoting the type bars.

A further object of the invention is to provide a construction of this kind in which the pivot wire may be taken out either from the rear or may be moved endwise in the pivot wire slot in either direction.

For the attainment of these ends and the accomplishment of other new and useful objects as will appear, the invention consists in the features of novelty in the construction, combination and arrangement of the several parts generally shown in the accompanying drawing and described in the specification, but more particularly pointed out in the appended claims.

In the drawings: Figure 1 is a front elevation of a type bar segment and pivot wire construction embodying my invention; Fig. 2 is a rear elevation of the same; Fig. 3 is a sectional view taken on the line 3-3 of Fig. 2, with a type bar shown in dotted outline; and Fig. 4 is a detail sectional view taken on the line 4-4 of Fig. 2, parts being broken away for clearness.

In pivoting the type bars of a typewriter machine, it is desirable that a simple, strong and efficient construction be provided, with certain adjustability and with as few parts as possible to produce the desired result.

This invention embodies a construction in which the pivot wire is bodily removed rearwardly from the segment, or, by loosening the adjusting means, may be moved longitudinally in the groove in either direction.

In the present embodiment of my invention, a type bar segment 5 is provided with a reinforcement 6 about its curved edge, in which are a plurality of radial type bar slots 7.

In one face of the segment, preferably the rear face, is a groove 8 for seating the universal bar (not shown), and another groove 9 with an undercut portion 10 for receiving a pivot wire 11. This groove 9 extends parallel to the curved edge of the segment and

to the extremities thereof, and is curved about the same center as the curvature of the outer edge of the segment, extending through the radial slots 7 of the segment.

The pivot wire 11 is formed at one extremity with a blunt end 12 and at the other extremity with a wedging or beveled type 13. The pivot wire is adapted to be received in the undercut groove 9 and is removable bodily from the groove or may be moved longitudinally in the groove and removed from the segment in that manner.

Extending from the front face of the segment 5 and into the groove 9 are a pair of screws, by means of which the pivot wire 11 is held firmly, but adjustably, in position. One of the screws, 14, is provided with an abutment portion 15, which is adapted to engage the blunt end of the pivot wire 11, and the other adjusting screw, 16, is provided with a conical or wedging extremity 17, which is adapted to engage the beveled extremity 13 of the pivot wire.

When the type bars, one of which is shown in dotted outline 18, are in position in the slots 7 of the segment, the blunt extremity of the pivot wire is moved against the abutment screw 14 at one end of the groove and the wedging screw 16 is forced against the other extremity of the pivot wire, thereby forcing the pivot wire firmly into the undercut portion of the groove and against the abutment screw 14.

If it is desired to remove only the type bars from one end of the segment, the adjusting screws 14 and 16 may be threaded out of the groove 9, and the pivot wire moved longitudinally in the groove in the other direction, thereby necessitating only the removal of a few of the type bars. If it is desired to remove all the type bars, the binding screws are loosened and the entire pivot wire and the type bars may be bodily removed from the rear of the segment.

What I claim is:

1. The combination with a type bar segment having an undercut groove therein, of a type bar pivot member, and means movable at right angles to the member to contact with the ends of the member to hold it in the groove.

2. The combination with a type bar segment having an undercut groove therein, of a type bar pivot member, and wedging means movable at right angles to the member for contacting with the ends of the mem-

ber to bind it releasably in the undercut groove.

3. The combination with a type bar segment having a groove in one face thereof, of a type bar pivot member, and means adjustable from the other face of the segment to contact with the ends of the member and bind the member releasably in the slot.

4. The combination with a type bar segment having an undercut groove in one face thereof, of a type bar pivot member, and means to force the member into the undercut portion to bind it in the groove.

5. The combination with a type bar segment having a groove in one face thereof, of a type bar pivot member adapted to be seated in the groove, an abutment to engage one end of the member, and an adjustable wedging device to engage the other end of the member at right angles thereto to hold it in the groove.

6. The combination with a type bar segment having an undercut groove in one face thereof, of a type bar pivot member adapted to be seated in the groove, an adjustable abutment extending from the other face of the segment into the groove to contact with one end of the member, and an adjustable wedging device extending from the other face of the segment and contacting with the other end of the member in the groove.

7. The combination with a type bar segment having a groove in one face thereof along the curved edge, of a type bar pivot wire adapted to be seated in the groove, and clamping members adjustable from the other face of the segment into the groove at right angles to the member and adapted to engage the ends of the member for wedging it firmly between them in the groove.

8. The combination with a type bar segment having an undercut groove in one face thereof curved about the center of curvature of the segment, of a pivot wire less in length

than the length of the groove, an abutment screw adjustable from the other face of the segment into the groove to engage one end of the pivot wire, and a wedging screw adjustable from the said other face of the segment into the groove to engage the other extremity of the wire to force the wire into the undercut portion and against the abutment screw.

9. The combination with a type bar segment having its outer edge formed with radial slots and with an undercut groove in one face thereof curved about the same center as the curvature of the segment and extending to the curved extremities of the segment, of a type bar pivot wire adapted to be seated in the groove and less in length than the groove in the segment, an abutment screw adjustable from the other face of the segment into the groove to engage one end of the pivot wire, and a wedging screw adjustable from the said other face of the segment into the groove at right angles to the wire to engage the other end of the pivot wire to bind it releasably in the undercut groove and against the abutment screw.

10. The combination with a type bar segment having a groove therein, of a type bar pivot wire having one blunt extremity and one tapered extremity, an adjustable abutment member adapted to engage the blunt end of the wire, and an adjustable wedging member to engage the beveled extremity of the pivot wire for binding it releasably in the groove against the abutment.

In testimony whereof I have signed my name to this specification, in the presence of two subscribing witnesses, on this second day of January, A. D. 1914.

ALVAH C. ROEBUCK.
